(57) **CLAIM**

The ornamental design for a portion of light-emitting diode unit, as shown and described.

DESCRIPTION

FIG. 1 is a perspective view of a portion of light-emitting diode unit showing my first example of the new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawing depict portions of the light emitting diode unit that form no part of the claimed design. The broken lines immediately adjacent to solid lines form a boundary of the claim, the space in-between the solid lines and broken lines form no part the claim.
